DESIGN FOR AN AMPHIBIAN CARGO PLANE OR SIMILAR ARTICLE

Joseph Lateana, San Francisco, Calif.

Application February 25, 1943, Serial No. 109,626

Term of patent 14 years

To all whom it may concern:

Be it known that I, Joseph Lateana, a citizen of the United States, residing at San Francisco, in the county of San Francisco and State of California, have invented a new, original, and ornamental Design for an Amphibian Cargo Plane or Similar Article, of which the following is a specification, reference being had therein to the accompanying drawings, forming part thereof, in which:

Figure 1 is a top plan view of an amphibian cargo plane or similar article, showing my new design.

Figure 2 is a front elevational view.

Figure 3 is a side elevational view.

I claim:

The ornamental design for an amphibian cargo plane or similar article, as shown.

JOSEPH LATEANA.
